TABULATING MACHINE

John T. Ferry, Ilion, N. Y., assignor to Remington Rand Inc., Buffalo, N. Y., a corporation of Delaware

Application October 26, 1938, Serial No. 237,007

5 Claims. (Cl. 197—133)

This invention relates to tabulators for statistical data cards and more particularly to automatic stop devices for stopping the tabulator after a predetermined number of line space operations by the printing carriage.

All present tabulators have automatic paper feeding mechanisms which advance the paper on the platen after each entry has been printed. Such mechanisms are disclosed in Patent No. 10 2,059,251 to W. W. Lasker and Patent No. 2,059,- 215 to E. H. Dreher. The present invention is an improvement on these mechanisms resulting in an automatic control over the lever for stopping the machine.

15 In certain classes of tabulator work it is advantageous to stop the machine after a certain number of items have been printed.

This is particularly true when the tabulator paper is later cut into sheet lengths and made 20 into loose leaf books. Such sheets are generally printed with a heading and assembled in a fan-fold stack with perforations for easy separation. Previous to this invention, stop cards were used which had to be inserted in the card stack at regular 25 intervals corresponding to the number of printable items on each sheet. It is obviously more convenient to make a mechanical setting in the printing head after which the tabulator will stop when the predetermined number of items 30 has been printed.

The invention resides in the provision of a settable trip cam attached to the hand lever hub of the paper feed mechanism and in a coacting latch system attached to the frame. One portion of the 35 latch system is connected by a series of links and bell-crank to a stop lever interponent which disengages a clutch and stops the tabulator mechanism.

The principal object of the invention is to provide 40 an automatic stop device for a tabulator.

Another object of the invention is to provide a settable lever which stops a tabulator after a predetermined number of line feed operations.

Another object is to provide a stopping means 45 for tabulators which may be easily reset manually.

Another object is to provide a latch mechanism coacting with the stop lever which will be reset when another bill form is moved into printing position by the paper injector lever.

Still another object is to provide an automatic stop device which may easily and conveniently be attached to the present design of tabulators without expensive alterations.

55 Other objects and structural details of the in-

vention will be apparent from the following description when read in connection with the accompanying drawings, wherein:

Fig. 1 is an elevational view of the head of a tabulator taken from the right hand side; 5

Fig. 2 is an elevational view of a portion of the head and the lower part of a tabulator taken from the left hand side;

Fig. 3 is an enlarged side view of the paper feed mechanism of the tabulator head similar to Fig. 1, 10 with parts broken away to disclose the details of the latch mechanism in the invention;

Fig. 4 is a sectional view taken along line 4—4 of Fig. 3;

Fig. 5 is a detail view of the latch mechanism 15 after the latch has been tripped and the clutch disengaged;

Fig. 6 is similar to Fig. 5 but indicating the position of the latch when the paper injector lever has been pulled down and the latch reset; 20

Fig. 7 is also similar to Fig. 5 but indicating the position of the latch when the paper injector lever is being returned to its initial position;

Fig. 8 is an enlarged detail view of the paper injector pawl mechanism after the lever has been 25 pulled down and the pawl unlatched.

The tabulating head shown in Fig. 1 has been described in the above mentioned patents. A complete tabulator design has also been disclosed in Patent No. 1,245,502 to James Powers. Since 30 the present invention deals only with improvements in the paper injector and the automatic stop device, the remainder of the tabulator mechanism will not be described. In Figs. 1, 3, and 4, a shaft 10 is journaled in the side frame 11 of the printing head. A printing platen (not shown) is secured to one end of this shaft and a hand knob 12 is fast on the other end, permitting manual control over the paper feed whenever necessary. Also secured to shaft 10 is a ratchet 40 13, and a spur gear 14 which meshes with a large driving gear 15. Secured to gear 14 is an aligner disc 16, and cooperating with the teeth of this disc is the usual detent roller 17 carried by a spring-drawn retaining lever 18. The primary 45 driving means for the paper feeding mechanism is delivered from a pitman 97 which moves upward during each printing cycle. A bell-crank 98, rocked by the pitman, oscillates a spring drawn rod 99, which communicates this motion through 50 a series of linkages, as follows: bell-crank 100, rod 101, bell-crank 102, rod 103, crank 93, pinion gear 94, gear 95, rod 104 to a pawl (not shown) which drives the printing platen through ratchet 13. In view of the fact that the above mecha- 55

nism is old and well known and described in detail in the above patent to Dreher, no detail description is believed necessary beyond the fact that the ratchet 13 is rotated by mechanism in the head each time printing takes place and the aligner disc 16 is provided to insure that the platen will stop in the correct printing position.

The driving gear 15 is secured to a hollow shaft 19 which turns on a stud shaft 20, mounted between the frame 11 and a supporting plate 21. Mounted on the hollow shaft 19 is a cylindrical sleeve 22 free to rotate on the shaft and having secured thereto an injector lever 23 which is urged in a clockwise direction by a spring 28. A settable arm 24 is also secured to the sleeve 22 and its position may be adjusted by means of the clamping screws 25. Mounted parallel to the large driving gear 15 and adjacent to it is a stationary gear segment 26, the teeth of which serve as a means for setting the injector lever 23. This stationary plate 26 is held in position by a screw 27 which anchors it to the plate 21 and by a hub 28 which is carried on the small end of shaft 20. The teeth of the segment 26 are the same size and pitch as the teeth of the gear 15.

Rotably mounted on the hub 28 is a settable limit arm 30 which is held in contact with the gear segment 26 by a helical spring 31, enclosed in a cup 32. Secured to limit arm 30 and meshing with the teeth of the gear segment 26 is a small three-toothed segment 33 which holds the arm in place after it has been adjusted. To change the setting of the arm 30, it is manually pulled away from the gear segment 26 by means of the knob 34 until the small segment 33 is disengaged. Then it is rotated on the hub 28 to its new setting and the small segment slipped into mesh again with the teeth on gear segment 26.

At the extremity of limit arm 30, a triangular yield plate 35 is pivotally mounted by means of the pin 36 and carries a limit pin 40 adapted to engage the hand lever assembly 23 when the latter is being reset.

Attached to hand lever 23 is a pivoted pawl 41 whose nose 42 engages the teeth of the driving gear 15 when the paper is being fed into and/or around the platen. The pawl 41 is pivoted on the pin 43 and is urged clockwise by the spring 44. Mounted above the pawl is a latch 45 which is pivoted on a screw 46 and adapted to hold the pawl 41 in engagement with the teeth of the gear 15 by means of a tooth 47 on plate 45 engaging a nose 48 on pawl 41. The spring 44 is anchored to the latch 45 in such manner as to exert a force tending to hold the latch and pawl together.

The latch mechanism (Figs. 3, 5, 6, and 7) which controls the stopping of the tabulator after the proper number of printing operations, is mounted on the side frame 11 adjacent to the shaft 20, and is a combination of four cooperating elements; an irregular base plate 48, a rocking plate 50, a sliding bar 51 and a pivoted pawl 52. The base plate 48 supports a pivot 53 for the clutch operating bell-crank 54 and a pivot bolt 55 on which the plate 50 rocks. A spring 56 has one of its ends anchored on a pin 57 attached to the plate 48 with its other end anchored to a pin 58 attached to plate 50 thereby stressing the plate 50 to rotate in an anti-clockwise direction around the bolt 55.

The plate 50 has mounted on its middle portion, two pins 59 and 61 which slide in slots 62 and 63 formed in bar 51. A spring 64 is employed to stress the bar 51 downwardly and for this pur-

pose is stretched between two studs, one on the plate 50 and the other on the side of bar 51. Another spring 65 is stretched between similar studs mounted on the upper end of plate 50 and the right hand side of pawl 52.

The bar 51 is provided with a limit screw 66 carried in an offset lug 67 and provided with a locking nut for permanent adjustment. At the lower extremity of the bar, a pivot 68 is mounted thereon, adapted to be engaged by a slot 70 formed in the ends of one of the arms of the bell-crank 54. A notch 71 is cut into the side of bar 51 and is adapted to be engaged by the nose 73 of a pawl 52, being adapted, when latched, to hold the bar 51 in its uppermost position, stressed against the action of spring 64 and holding the bell-crank 54 in the position of Fig. 7.

The pawl 52 is pivoted on pin 66 and has a nose 72 extending toward the arm 24 and coplanar with it. The pawl is triangular in shape and its apex is formed with a nose 73 which coacts with the notch 71 as described above.

The lower arm of bell-crank 54 is connected to a link 74 which in turn is connected to a bell-crank 75 (Fig. 2) pivoted on the rear of the machine. The lower arm of bell-crank 75 is connected to a link 76 which is adapted to operate a trip lever 77 which actuates the control mechanism of the tabulator.

The control mechanism and associated clutch 30 disengaging mechanism is fully described in U. S. Patent No. 2,044,119, issued to W. W. Lasker and shown therein in Figs. 5, 15, and 16. The essential features of this structure reside in a cam 78 which makes one revolution for each cycle of the tabulator. As the rise of cam 78 passes under a roller 80 on a follower arm 81, a vertical arm 82 is moved upwardly for a short distance. As long as the machine is to continue in its normal running condition, the vertical arm 82 will idle, 40 but when it is decided to stop the machine, an interponent 83 is interposed above the arm 82 so that the upward motion will be transmitted to one end of a rocker arm 84, thereby rocking it about its pivot and giving a downward motion to 45 link 85. This link is pivotally connected to the extremity of a crank 87 which is secured to the clutch shaft 86. Also secured to clutch shaft 86 is an arm 105 which controls the position of a movable clutch plate 106. The other clutch plate 50 107 is driven by a belt 108 and an electric motor 109 which is kept running continually. The clutch plate 106 is disengaged when the shaft 86 is rocked counter-clockwise thus stopping the tabulator. The interponent 83 is pivotally 55 mounted on a lever 88 which extends below the intermediate plate 90 and is adapted to be engaged by various levers and cams which are part of the manual stopping mechanism controlled by button 91.

The operation of the automatic stopping device is as follows: Paper is fed into and around the platen and aligned properly for the first entry. The limit arm 30 is set for total form length and the hand lever 23 is set back until the pawl 65 41 comes in contact with the limit pin 40, thereby causing the nose 42 to engage one of the teeth on driving wheel 15.

The arm 24 is adjusted on the sleeve 22 so that, after the required number of items have been 70 printed, the arm will rotate the pawl 52 by contact with the nose 72. The cards are stacked in the magazine and the machine started by pressing the button 91.

As each printing operation is concluded, the 75

series of links described above causes a crank 93 to be turned through a small angle, which movement is transferred to the printing carriage by means of gears 94 and 95. As this mechanism is fully described in the above patent to Dreher, no detailed description will be included here. By other linkages (not shown), the ratchet wheel 13 is advanced one space, thereby turning the platen and moving the paper to the next printing position. As the shaft 10 is rotated the equivalent of one line space on the platen, the large gear 15 which meshes with gear 14 is rotated counter-clockwise carrying the hand injector lever 23 and adjustable arm 24 in the same direction. The printing and spacing operations continue until the arm 24 comes in contact with the nose 72 of pawl 52 and rotates it clockwise about its pivot 60. This disengages the nose 73 from the notch 71 and the bar 51 is pulled downwardly by the action 10 of spring 64 as shown in Fig. 5. This motion is communicated by bell-crank 54 to link 74 which is connected by other linkages to the trip lever 77. This lever is rotated clockwise and rocks the interponent 83 into the path of the vertical arm 25 82, thereby rocking arm 84 and disengaging the clutch.

The position of the various parts of the latch assembly at the moment of tripping is shown in Fig. 5.

To continue printing on the next paper heading, the machine must be reset manually by the operator. This is done by pulling the injector lever 23 down all the way and then letting it spring back to its initial position as shown in Fig. 3. When the lever is drawn down, the nose 42 is still in mesh with the gear 15 and the platen is rotated sufficient to carry a new heading into position ready for the first printed item. At the end of this downward movement, the latch 45 is engaged by the screw 27, and rotated around its pivot 46 until the pawl 41 is released from the tooth 47 (see Fig. 8). Both the latch and the pawl swing in a clockwise direction, releasing the nose 42 of pawl 41 from the gear 15 thus permitting the lever 23 to fly back under the tension of helical spring 29 (Fig. 4).

As the lever 23 is stopped by the limit pin 40, the force of the blow acts against the inclined surface of pawl 41, causing it to be rocked counter-clockwise so that its nose 49 is again latched under the tooth 47 and nose 42 is in mesh with the gear wheel 15.

Fig. 6 shows the position of the latch assembly when the shaft 20 has been rocked by the hand lever 23 to its full extent of travel, and is in a position to return to normal again. During the interval in operation between the positions shown in Figs. 5 and 6, the arm 24 has rotated the pawl 52 a distance sufficient to permit the arm to pass the nose 72. During this rotation the upper edge of the arm lifts the sliding bar 51 by means of the set screw 66 until said bar is again engaged by the pawl 52. The lifting of the bar 51 also rotates the bell-crank 54 and by means of the linkages as previously set forth, rocks the bell-crank 77 counter-clockwise out of the path of lever 88. This action does not start the machine again as has been explained in Patent 2,044,119, referred to above. The operator waits until the arm 23 has been returned to its normal position, checks on the position of the injected paper form and then starts the machine again by pressing the starting button 91.

Fig. 7 shows the position of the latch assembly 75 as the hand lever is being returned to its normal

or starting position. On the return stroke the arm 24 is traveling in a clockwise direction and as the nose thereof comes in contact with the nose 72 of the pawl 52, the inclined surfaces of each cause the pawl, together with the bar 51 and the plate 50, to be rotated slightly about the screw 55 so as to allow the arm 24 to pass. The spring 56 returns the latch assembly to its normal position after disengagement and the mechanism is ready for another cycle of operation.

While I have described what I consider to be a highly desirable embodiment of my invention, it is obvious that many changes in form could be made without departing from the spirit of my invention, and I, therefore, do not limit myself to the exact form herein shown and described, nor to anything less than the whole of my invention as hereinbefore set forth, and as hereinafter claimed.

What I claim as new, and desire to secure by Letters Patent, is:

1. In a machine of the class described, employing punched data cards for the tabulation of data, having a paper feeding mechanism operated through a clutch and capable of causing a paper feeding operation for each cycle of the machine, the combination of an arm adjustably secured to a shaft which is rotated by said feeding mechanism; a bar operatively connected by mechanical linkages to said clutch; a pawl adapted to retain said bar in clutch operative position until the pawl is engaged by said adjustable arm, whereby said bar is released after a predetermined number of paper feeding operations have occurred; a lug on said bar adapted to be engaged and lifted by said arm; and a manually operable lever connected to said feeding mechanism by a ratchet gear, whereby said bar may be manually reset in clutch operative position after having been released.

2. In a machine of the class described, employing punched data cards for the tabulation of data, having a paper feeding mechanism operated through a clutch and capable of causing a paper feeding operation for each cycle of the machine, the combination of an arm adjustably secured to a portion of the paper feeding mechanism and adapted to rotate as paper is fed through the machine, a bar operatively connected by mechanical linkages to said clutch; a pawl adapted to retain said bar in clutch operative position until the pawl is engaged by said adjustable arm, whereby said bar is released after a predetermined number of paper feeding operations have occurred; a lug on said bar adapted to be engaged and lifted by said arm; and a manually operable lever connected to said feeding mechanism by a ratchet gear, whereby said bar may be manually reset in clutch operative position after having been released.

3. In a machine of the class described, employing punched data cards, the combination of a paper feeding mechanism operated through a clutch, means for causing a paper feeding operation for each cycle of the machine, an adjustable arm secured to a portion of the paper feeding mechanism and adapted to rotate as paper is fed through the machine, a bar mechanically connected to said clutch, a pawl adapted to retain said bar in clutch operative position, a lug on said bar adapted to be engaged and lifted by said adjustable arm, means for releasing said bar after a predetermined number of paper feeding operations, said means comprising the cooperative action of said lever on said pawl, and a manually

- operable lever connected to said feeding mechanism whereby said bar may be manually re-engaged in clutch operative position.
4. In a machine of the class described, employing punched data cards, the combination of a paper feeding mechanism operated through a clutch, means for causing a paper feeding operation for each cycle of the machine, an adjustable arm secured to a portion of the paper feeding mechanism and adapted to rotate as paper is fed through the machine, a bar mechanically connected to said clutch, a pawl for retaining said bar in clutch operative position until the pawl is engaged by said arm, a lug on said bar adapted to be engaged and lifted by said adjustable arm, and a manually operable lever connected to said feeding mechanism whereby said bar may be manually engaged in clutch operative position.

5. In a machine of the class described, employing punched data cards, the combination of a paper feeding mechanism operated through a clutch, means for causing a paper feeding operation for each cycle of the machine, an adjustable arm secured to a portion of the paper feeding mechanism and adapted to rotate as paper is fed through the machine, a bar mechanically connected to said clutch, a pawl adapted to hold said bar in clutch operative position until said pawl is rocked clear by said adjustable arm, thereby releasing said bar and disengaging said clutch, and a manually operable lever mechanism co-operating with a lug on said bar for resetting the bar in clutch operative position after having been released.

JOHN T. FERRY.
